UNITED STATES PATENT OFFICE

GEORGE E. PICKUP, OF NEWARK, OHIO, ASSIGNOR TO THE WEHRLE COMPANY, OF
NEWARK, OHIO, A CORPORATION OF OHIO

DESIGN FOR A HEATING STOVE

Application filed July 12, 1930. Serial No. 36,330. Term of patent 7 years.

To all whom it may concern:

Be it known that I, GEORGE E. PICKUP, a citizen of the United States, residing at Newark, in the county of Licking and State of Ohio, have invented a new, original, and ornamental Design for a Heating Stove, of which the following is a specification, reference being had to the accompanying drawing, forming part hereof.

The drawing is a perspective view show-

ing a heating stove of my new design. Both side walls of the heater of which only one is shown are similar, and the inclined front and rear sides of the top are plain and merge into a plain upper top surface.

I claim:

The ornamental design for a heating stove, substantially as shown and described.

GEORGE E. PICKUP.
